UNITED STATES PATENT OFFICE.

GEORGE P. CARROLL, OF BRIDGEPORT, CONNECTICUT.

RHEOSTAT-CONTROLLER.

1,130,476.

Specification of Letters Patent.

Patented Mar. 2, 1915.

Original application filed April 12, 1907, Serial No. 367,836. Divided and this application filed May 6, 1909. Serial No. 494,298.

To all whom it may concern:

Be it known that I, GEORGE P. CARROLL, a citizen of the United States, residing at Bridgeport, in the county of Fairfield and State of Connecticut, have invented a new and useful Rheostat-Controller, of which the following is a specification.

This application is a division of my application entitled Automatic compression refrigerating system, filed April 12, 1907, Ser. No. 367,836.

In the present application my invention relates to improvements in the apparatus for controlling a rheostat, especially when used in connection with a motor, or other apparatus, used to operate a refrigerating machine.

The purpose of my present invention is to economize current and to provide an electric device such that a breaking of the branch current through the rheostat winding will break the main current through the rheostat arm.

My purpose further is to provide a simple thermostatic control of the rheostat, useful in refrigerating systems.

The means employed for accomplishing these ends are as will appear. There are also certain detail improvements in construction as will appear.

In the drawings the figure is a diagrammatic representation of my invention showing the parts in detail and their connections.

An expansion coil 1 is located in whatever place is to be refrigerated and leads into a compressor 2, being provided near where it emerges from such place with a hand shut off valve 3. The compressor is preferably belt driven by a motor 4. When the compressor is in operation it draws spent gas from the coil, compresses the gas, and forces the compressed gas through a high pressure pipe 5, an oil separator 6, and into a double pipe condenser 7. Thence the condensed gas, now in liquefied form if ammonia is the refrigerant, passes by a pipe 8 to a receiver 9. And thence a liquid pipe 10 leads to an electric expansion valve E, more fully shown and described in Figs. 2, 3 and 4 of said former application and in the description relating thereto. The valve E is also fully shown and described in the United States Patents to me Nos. 924,964 and 925,081, dated June 15, 1909. From the

valve E a pipe 11 leads to a pressure regulating valve P, at the inlet end of the coil 1, which valve is more fully shown and described in said Fig. 2 and in the description relating thereto. The valve P is also fully shown and described in the United States Patent to me No. 906,508, dated Dec. 15, 1908. A hand valve 12, near the inlet end of the coil 1, may be used, when desired, to entirely shut off the coil.

A cooling water pipe 13 leads through the condenser 7 into the water jacket 14 of the compressor 2, whence a pipe 15 carries the heated water to waste. The inlet to the pipe 13 is controlled by an electric water valve W, more fully shown and described in Figs. 5 and 6 of said former application and in the description relating thereto. The valve W is also fully shown and described in the United States Patent to me No. 906,509, dated Dec. 15, 1908. A pipe 16, provided with a hand valve 17^b, leads from any source of cold water supply into the valve W. A hand valve 18^b is placed in the pipe 13 between the condenser 7 and the water jacket 14; it is used to shut off the parts when necessary. Under operating conditions the valve 18^b is wide open and the valve 16 is opened sufficiently to supply a maximum of condensing water at such times as the compressor is actually running; and the valve W is open in the manner to be described. An oil drain pipe 19^b leads from the foot of the oil separator 6 into the base of the compressor 2 and is controlled by a hand valve 20^b, normally closed. In the pipe 5 between the compressor 2 and the oil separator 6 is placed a hand stop valve 21^b; between the oil separator and the condenser 7 is placed a hand stop valve 22^b; between the condenser and the receiver 9 is placed a hand stop valve 23^b; and just beyond the receiver in the pipe 10 is placed a hand stop valve 24^b. Under normal conditions of operation the valves 3, 21^b, 22^b, 23^b, 24^b and 12 are wide open.

Beginning here the parts are lettered and numbered nearly as in said former application.

From a generator G mains 17 lead through a hand switch S to and back again from the motor 4. Between the switch and the motor, in the upper side of the mains as shown, is placed an overload automatic

2
circuit breaker A. Between the circuit breaker and the motor is placed a starting rheostat R, having a solenoid winding 18.

The casing of the valve E has between its ends a valve seat adapted to be closed by a vertically moving stem and needle valve 20, which a coiled spring 21 tends to close upon its seat. Pivotally secured to the valve stem is a horizontal inner lever 24, turning on a shaft 25 journaled in and passing through the wall of the casing. An outer lever 26 is secured to the outer end of the shaft and extends in a horizontal direction opposite to that of the inner lever.

Pivoted at 27 is a three part lever 28 having its main arm 29 extending horizontally toward and terminating in a position just above the outer end of the lever 26. An adjustable screw 30 at the end of the arm 29 determines the extent to which the lever 28 may depress the lever 26 and lift the lever 24 and the valve 20. Substantially at right angles to the main arm, an upper arm 31 extends upward from the pivot 27. A third arm, and a connected automatic device extend downwardly from the pivot and are operative to break a current through the electromagnet 33, to be described, as fully set forth in the particular drawings and descriptions of the valve E above referred to; but they could be dispensed with so far as the operation of the valve E is concerned and are no part of the structure which is the basis of the present invention.

35 An electromagnet 33, placed under the arm 29, when energized, depresses the same, in opposition to a spring 34, and also throws the arm 31 to the left. A pivoted dog 35 drops upon and locks the arm 31, after the latter has been thrown to the left, so as to hold the lever 28 in position after the magnet 33 is no longer energized. An electromagnet 43, placed over the dog 35, when energized, lifts the dog and permits the spring 34 to lift the arm 29 and to throw the arm 31 to the right and out of engagement with the dog 35 after the magnet has ceased to be energized.

50 The function of the valve P is to determine the pressure in the coil 1 when the valve E is open; and for present purposes it may be assumed, with ammonia as the refrigerant, that the valve is so adjusted as to maintain a pressure of 30 lbs.

55 The casing of the valve W has between its ends a valve seat adapted to be closed by a vertically moving valve 57 with a stem 58 extending upward through the casing. A spring 60, coiled about the stem, tends to keep the valve closed. On the outer part of the stem are three collars, one above another. Preferably these collars are longitudinally adjustable on the stem. A solenoid 65 has a core 66 insulated on top and provided

just below its top. A dog 68, pivoted on the lower end of the core 67, rests, when the core is depressed, on a pin 71 so as to be free of the stem 58. But when the core is lifted, the dog presses against the stem so as to lock whichever collar may be above it.

5 The core 66, when energized, lifts the dog 68, so as to free the stem 58, and the stem 58, in turn, lifts the valve 57. A switch 73, pivoted at the left of its center, has a spring 76 that tends to lift its left end, which is insulated, and to depress its right end. The right end of the switch 73 has on its lower side a contact surface adapted to make contact with the upper surfaces of a contact piece 77, having its left and right ends insulated from each other. A pivoted spring locking device 79 tends to lock the left end of the switch 73 so as to hold its right end off of the piece 77 and the core 66, on being energized, operates to lift the switch into this lockable position.

15 A detent lever 83, pivoted at its lower end, is acted upon by a spring 85 so as to tend to turn to the right. Just above its pivot, on the right, the lever has a detent adapted to engage from beneath and to lock in an elevated position whichever one of the collars on the stem it may be under. The extreme top of the lever 83, when it is turned to the left, operates on the device 79 so as to overcome the tendency of the latter and to unlock it from engagement with the switch 73. An electromagnet 90, when energized, operates on the lever 83 so as to pull it to the left in opposition to the spring 85.

20 From the mains 17, through a resistance 91, a wire 92 leads to the solenoid 65, from which a wire 93 leads to the right end of the piece 77. A wire 94 leads from the conductor part of the switch 73 to the mains 17 on the other side of the motor 4. A wire 95 leads from the wire 93 to a circuit breaker 96 and thence through a winding and resistance 97, having a core 98, to the wire 94. The part 97 operates on the core 98 so as, by opening the circuit breaker, to break the circuit whenever the current exceeds a predetermined limit. The circuit breaker has an arm 99, which serves the double purpose of being a hand lever, on being lifted, to close the circuit and also is adapted to be lifted with like effect by engagement with the projecting lever end of a core 100 when a solenoid 102, containing the core, is energized. A wire 103 leads from the wire 93 through a resistance 104 to the wire 94. A wire 105 leads to and through the solenoid 102 from the wire 92 to the left end of the piece 77.

25 As part of the rheostat R, an arm 51^a is pivoted near its left end on an insulated pivot 52^a and near its center is pivoted to but is insulated from a core 53^a within and magnetizable by the winding 18. Pivoted to the short and insulated end of the arm 51^a is a dash pot device 54^a, operating to somewhat retard the upward movement of the arm when the core is energized. A

series of contacts 55^a are connected one to another in ascending order by divisional or sub-resistances 56^a. The highest contact above the highest resistance is connected with the end of the mains 17 leading from the circuit breaker A. Another end of the mains 17, leading to the motor 4, is connected with a part of the arm 53^a near the pivot 52^a, the arm being a conductor from that point to its extreme right end. When the core 53^a is lifted it makes contact with one contact 55^a after another, beginning with the lowest, until all the resistances are cut out and a full current passes through the mains 17.

From the mains 17, between the circuit breaker A and the contacts 55^a, through a resistance 106, a wire 107 leads through the winding 18 to a starting contact 108, where contact can be made through a hand switch 109 back to the generator by a wire 57^a. Such a contact energizes the winding 18 to turn on the full current for starting and running the motor 4. The hand switch is also adapted to make a stopping contact at 110 and a third contact at 111, the latter being as shown. Through a resistance 112 a wire 113 leads from the mains 17, between the circuit breaker A and the resistance 106, to and through the magnet 90 to the contact 110. From the mains 17, between the pivot 52^a and the motor 4, a wire 114 leads through a resistance 58^a to and through the magnet 33 to the wire 57^a and thence back to the mains. From the wire 113, between the resistance 112 and the magnet 90, a wire 115 leads to and through the magnet 43 back to the wire 113 on the other side of the magnet 90.

In operative proximity to the coil 1 is mounted a thermostat T of any approved type. In the form shown it consists of a rod 116, subject to expansion or contraction with increases or decreases of temperature, attached to the short end of a lever 117, pivoted at 127 and adapted to make one contact with a starting contact 118 and another contact with a stopping contact 119. The lever 117 is a conductor throughout its long end as far as its pivot, which is insulated.

A solenoid winding 120 contains a core 121 toothed at its top and having a cross switch 122 attached to its lower end. When the core is lifted, by the energization of the winding 120, its tooth is engaged by a detent 123 so as to hold the core and its switch in an elevated position. The detent, under the action of gravity, tends to turn to the left so as to engage the tooth of the core 121, if the core has been lifted, and, in any event, so as to fall against a limiting pin 59^a. An electromagnet 124, on being energized, temporarily turns the detent 123 to the right.

From the wire 107, between the winding

18 and the contact 108, a wire 125^a leads to a switch contact 60^a; and from a switch contact 61^a a wire 125^b leads to the wire 57^a. When the core 121 is lifted the switch 122 closes the contacts 60^a and 61^a. From the wire 113, between the resistance 112 and the magnet 90, a wire 126 leads to and through the winding 120 to the contact 118. A wire 127^a leads from the conductor part of the lever 117, near its pivot 127, to the contact 111. From the wire 126, between the resistance 112 and the winding 120, a wire 128 leads to and through the magnet 124 to connect at a point 129 with the wire 113 between the magnet 90 and the contact 110. A wire 130 leads from the wire 128 to the contact 119.

The parts are so constructed in relation to each other that a greater current is required to pass through the resistance 104 than through the resistance 97 and the circuit breaker A does not operate until after the passage of a current through the resistance has failed to open the circuit breaker 96.

The contacts 110 and 119 are adjustable so that they can be moved nearer together to effect a narrow temperature range of operation by the thermostat T and wider apart to effect a broader range. Also by moving the contacts upward, the thermostat acts within a lower temperature range; and by moving them downward, it acts within a higher temperature range.

The method of operation is as follows: Assume that the contacts 118 and 119 are so adjusted that at 38 degrees the thermostat makes contact with the contact 118; and at 35 degrees with the contact 119. In the positions of the parts as shown, the compressor 2 is not running, the valves E and W are closed, and the temperature about the thermostat T is rising to 38 degrees. At that temperature the thermostat through its lever 117, which of course is essentially a switch just as is the switch 109, makes contact with the starting contact 118. Thereupon a slight current from the mains 17 passes through the wire 113, the resistance 112, the wire 126, the winding 120, the contact 118, the lever 117, the wire 127^a, the contact 111, the switch 109 and the wire 57^a back to the mains. The energization of the winding 120 lifts the core 121 into holding engagement with the detent 123 and also close the switch 122. The closing of the switch causes a current to pass through the wire 107, the resistance 106, the winding 18, the wire 125^a, the contact 60^a, the switch 122, the contact 61^a and the wire 125^b back to the wire 57^a and the mains. The energization of the winding 18 lifts the core 52^a and the arm 57^a gradually turns on the full current through the mains 17 to start and to speed up the motor 4 and the compressor 2. Simultaneously with the arm 51^a making

its ascending contacts with the contacts 56^a, the valves E and W are opened. The valve E is opened by a current through the wire 114, the resistance 58^a, the magnet 33 and the wire 57^a. The action of the energized magnet 33 in opening the valve E has been fully explained. The valve W is opened by a current from the mains 17 through the wire 92, the resistance 91, the winding 65, the wire 93, wire 95, the circuit breaker 96, the resistance 98 and the wire 94 back to the mains. The consequent energization of the winding 65 lifts the core 66 and the consequently lifted dog 68 lifts the middle collar 15 on the stem 58 so as to open the valve W. The lever 83 springs into place to hold the stem 58 and the valve 57 in their elevated position. The operation of the other parts of the valve W to cause a greater or less flow of water according to increases or decreases of current through the mains 17, and with a different pre-adjustment of certain parts of the valve, are fully explained in either of its said other descriptions. But it 25 is not deemed necessary to here repeat such description. The above description will suffice for an understanding of my present invention.

With the valves E and W open, vaporizing ammonia passes through the coil 1 and the expanded gas is drawn from the coil by the compressor 2, whence it is forced in dense condition into the condenser 7. Cooling water through the pipe 13 liquefies the 35 hot gas, which as a liquid flows into the receiver 9. Presently, as the surrounding medium is cooled down by the coil 1, the lever 117 leaves the contact 118 and current is no longer passing through the winding 120. 40 But the detent 123 continues to keep closed the switch 122 so that the full current continues to pass through the arm 51^a; and the compressor 2 continues to operate at full capacity. Finally, however, the lever 117 45 makes contact with the stopping contact 119. Thereupon a slight current from the mains 17 passes through the wire 113, the resistance 112, the wire 126, the wire 128, the magnet 124, the wire 130, the contact 119, 50 and the lever 117 back, as at starting to the mains. The energization of the magnet 124 temporarily turns the detent 123 to the right so as to release the core 121. Thereupon gravity opens the switch 122 and no 55 current passes through the winding 18. Thereupon gravity opens the arm 51^a and current through the mains 17 ceases, causing the motor 4 and compressor 2 to slow down and stop. But simultaneously with 60 the passage of a current through the magnet 124, a current passes through the wire 113, the resistance 112, the wire 115, the magnet 43, the wire 113 again, the wire 128 and the wire 130, where it unites with the current 65 through the magnet 124 back to the mains.

And also simultaneously a current passes through the wire 113, the winding 90 and the wire 128 where it unites with the current through the magnet 43 back to the mains. The energization of the magnet 43 lifts the 70 dog 35 so as to close the valve E, as previously explained. The energization of the magnet 90 turns the lever 83 to the left and releases the stem 58 so that the spring 60 seats the valve 57 and the valve W is closed. The temperature about the thermostat T now begins to rise until the lever 117 is in the position shown and the cycle of operation is complete.

If it is desired to control the rheostat R by hand and to short circuit the thermostat T, the switch 109 is turned into contact with the starting contact 108 and a current passes through the entire length of the wire 107 so as to energize the winding 18 and to close the arm 51^a with the same refrigerating results as before. And to stop the compressor 2, the switch 109 is turned into contact with the closing contact 110 with the same closing results as before. Thus a thermostatic control of the rheostat does not interfere with its hand control.

It is to be noted that, in starting the refrigerating part of the cycle, no current passes through the winding 120 after the lever leaves the contact 118, that, when the lever 117 touches the contact 119, the branch current through the winding 18 and the main current through the mains 17 cease; and that when the lever 117 leaves the contact 119 the current through the magnet 124 ceases. It also is to be noted that while the motor 4 and the compressor 2 are running, the arm 51^a is held elevated, in its connecting position, solely by means of a current through the winding 18. This is a safety position, inasmuch as a stopping of the current through the winding 18, whether by the lever 117 touching the contact 119 or by other means, releases the arm 51^a and stops the motor 4. It is also to be noted that the valves E and W are not essential to the present invention, but that the flow of refrigerant and the flow of condensing water may be regulated by some other means.

What I have invented and what I desire to have protected by Letters Patent is expressed in claims as follows:

I claim:

1. In combination two conductors adapted to be connected in series, a rheostat arm adapted to so connect said conductors, a main electric device when energized causing said arm to so connect said conductors, said arm disconnecting said conductors upon the cessation of such energization, two branch conductors adapted when connected in series to transmit an energizing current to said device, a secondary electric device operating upon the passage of a current

through one part thereof to so connect said branch conductors and upon the passage of a current through another part thereof to disconnect said branch conductors, wires to 5 and from said first part of said secondary electric device, wires to and from said second part of said secondary electric device, and a thermostatic member operating upon a predetermined change of temperature in 10 one direction to close a circuit in said former wires and upon a predetermined reverse change of temperature to close a circuit in said latter wires.

2. In combination two conductors adapted 15 to be connected in series, a rheostat arm adapted to so connect said conductors, a main electric device when energized causing said arm to so connect said conductors, said arm disconnecting said conductors upon the 20 cessation of such energization, two branch conductors adapted when connected in series to transmit an energizing current to said device, a secondary switch tending to be open but on being closed so connecting said branch conductors, a core operatively connected to said secondary switch, a magnet winding operating upon being energized to energize said core so as to close said secondary switch, a detent device operating 25 upon the cessation of the energization of said winding to hold said secondary switch closed but nevertheless remaining subject to retraction so as to permit said secondary switch to open, another magnet winding operating 30 upon being energized to retract said detent device, wires to and from said first magnet winding, wires to and from said second magnet winding, and a thermostatic member operating upon a predetermined change of temperature in 35 one direction to close a circuit in said former wires and upon a predetermined reverse change of temperature to close a circuit in said latter wires.

3. In combination an electric motor, two 45 conductors adapted when connected in series to transmit an operating current to said motor, a rheostat arm adapted to so connect said conductors, a main electric device when energized causing said arm to so connect 50 said conductors, said arm disconnecting said conductors upon the cessation of such energization, two branch conductors adapted when connected in series to transmit an energizing current to said device, a secondary 55 electric device operating upon the passage of a current through one part thereof to so connect said branch conductors and upon the passage of a current through another part thereof to disconnect said branch conductors, wires to and from said first part of said 60 secondary electric device, wires to and from said second part of said secondary electric device, and a thermostatic member operating upon a predetermined change of temperature in one direction to close a circuit 65

in said former wires and upon a predetermined reverse change of temperature to close a circuit in said latter wires.

4. In combination an electric motor, two conductors adapted when connected in series 70 to transmit an operating current to said motor, a rheostat arm adapted to so connect said conductors, a main electric device when energized causing said arm to so connect said conductors, said arm disconnecting said 75 conductors upon the cessation of such energization, two branch conductors adapted when connected in series to transmit an energizing current to said device, a secondary switch tending to be open but on being closed so connecting said branch conductors, a core operatively connected to said secondary switch, a magnet winding operating upon being energized to energize said core so as to close said secondary switch, a detent 80 device operating upon the cessation of the energization of said winding to hold said secondary switch closed but nevertheless remaining subject to retraction so as to permit said secondary switch to open, another 85 magnet winding operating upon being energized to retract said detent device, wires to and from said first magnet winding, wires to and from said second magnet winding, and a thermostatic member operating upon a predetermined change of temperature in 90 one direction to close a circuit in said former wires and upon a predetermined reverse change of temperature to close a circuit in said latter wires.

5. In combination an electric motor, a compressor operatively connected with said motor, a refrigerant condensing and storing apparatus leading from said compressor, an expansion coil leading from said apparatus 105 into said compressor, means for regulating the expansion of refrigerant from said apparatus into said coil, two conductors adapted when connected in series to transmit an operating current to said motor, a rheostat arm adapted to so connect said conductors, a main electric device when energized causing said arm to so connect said conductors, said arm disconnecting said conductors upon the cessation of such energization, two branch conductors adapted when connected in series to transmit an energizing current to said device, a secondary electric device operating upon the passage of a current through one part thereof to so connect said branch conductors and upon the 110 passage of a current through another part thereof to disconnect said branch conductors, wires to and from said first part of said secondary electric device, wires to and from 115 said second part of said secondary electric device, and a thermostatic member affected by the expansion of refrigerant in said coil and operating upon a rise of temperature to 120 a predetermined high limit to close a circuit 125

in said former wires and upon a fall of temperature to a predetermined low limit to close a circuit in said latter wires.

6. In combination, an electric motor, a compressor operatively connected with said motor, a refrigerant condensing and storing apparatus leading from said compressor, an expansion coil leading from said apparatus into said compressor, means for regulating the expansion of refrigerant from said apparatus into said coil, two conductors adapted when connected in series to transmit an operating current to said motor, a rheostat arm adapted to so connect said conductors, a main electric device when energized causing said arm to so connect said conductors, said arm disconnecting said conductors upon the cessation of such energization, two branch conductors adapted when connected in series to transmit an energizing current to said device, a secondary switch tending to be open but on being closed so connecting said branch conductors, a core operatively connected to said secondary switch, a magnet

winding operating upon being energized to 25 energize said core so as to close said secondary switch, a detent device operating upon the cessation of the energization of said winding to hold said secondary switch closed but nevertheless remaining subject to 30 retraction so as to permit said secondary switch to open, another magnet winding operating upon being energized to retract said detent device, wires to and from said first magnet winding, wires to and from said second magnet winding, and a thermostatic member affected by the expansion of refrigerant in said coil and operating upon a rise of temperature to a predetermined high limit to close a circuit in said former wires 40 and upon a fall of temperature to a predetermined low limit to close a circuit in said latter wires.
